REFRIGERATION CONTROL SYSTEM

Charles B. Spangenberg, Minneapolis, Minn., assignor to Minneapolis-Honeywell Regulator Company, Minneapolis, Minn., a corporation of Delaware

Application September 30, 1938, Serial No. 232,574

26 Claims. (Cl. 62—4)

This invention relates to refrigeration control systems and to improvements in the component parts thereof.

The primary object of this invention is to provide an improved control system for a refrigerating apparatus having evaporator means for cooling a medium and a compressor wherein the condition of the medium being cooled is maintained at the desired values, wherein starting of the compressor is prevented until the evaporator means has defrosted and the pressure on the high pressure side of the refrigerating apparatus has decreased to a predetermined low value, wherein the compressor may be stopped when either the pressure on the low pressure side of the evaporator decreases to a predetermined low value or the pressure on the high pressure side of the refrigerating apparatus increases to a predetermined high value and wherein an automatic resetting overload cut out is provided to stop the compressor upon the occurrence of overload conditions.

Other objects and advantages will become apparent to those skilled in the art upon reference to the accompanying specification, claims and drawings, in which:

Figure 1 is a diagrammatic illustration of one form of the control system applied to a refrigerating apparatus.

Figures 2 and 3 are modified forms of a portion of Figure 1 for accomplishing substantially the same results as are accomplished in Figure 1.

Figure 4 illustrates diagrammatically a modification of the control system of Figure 1 for accomplishing a slightly different sequence of control, and

Figure 5 is a diagrammatic illustration of the manner of applying the overload cut-out mechanism to the control system of application Serial No. 101,107, filed September 16, 1936, by Wayland R. Miller.

Referring now to Figure 1 the medium to be conditioned or cooled by the refrigerating apparatus is shown to be air within an enclosure 10. The medium in the enclosure 10 is cooled by a cooling coil preferably in the form of an evaporator 11. Refrigerant is supplied to and withdrawn from the evaporator 11 by means of a refrigerating apparatus generally designated at 12 which may comprise a compressor 13 operated by an electric motor 14. The compressor 13 delivers compressed refrigerant through a high pressure line 15 into a condenser 16 and the condensed refrigerant is collected in a receiver 17. Liquid

refrigerant flows from the receiver 17 through a liquid line 18 into the evaporator 11 and the evaporated refrigerant is withdrawn from the evaporator 11 through a low pressure or suction line 19 by the compressor 13. An expansion valve 20 controls the supply of refrigerant to the evaporator 11 and it may be of the thermostatic type having a bulb 22 located at the discharge side of the evaporator and containing a volatile fluid and connected by a capillary tube 21 to the expansion valve. The construction thus far described is conventional in the art and therefore a further description thereof is not considered necessary it being sufficient to state that the evaporator 11 performs a cooling function when the compressor 13 is placed in operation.

The compressor motor 14 and hence the refrigerating apparatus is controlled by a control means responsive to the condition of the medium in the enclosure 10 and is shown to be a thermostatic control means generally designated at 24. The compressor motor 14 is also controlled by a controller generally designated at 25 operating in response to changes in pressure on the high pressure side of the refrigerating apparatus and pressure on the low pressure side of the refrigerating apparatus, the latter being an indication of evaporator temperature. An overload cut-out mechanism generally designated at 26 also controls the operation of the compressor motor to protect the same against overload conditions.

The temperature responsive controller 24 may comprise a bellows 28 containing a volatile fluid for operating a lever 29 against the action of an adjustable tension spring 30. The lever 29 in response to changes in temperature closes and opens a mercury switch 31. For purposes of illustration it is assumed that when the temperature of the medium within the enclosure 10 rises to 42° the mercury switch 31 is tilted to the closed position and when the temperature decreases to 40° the mercury switch 31 is tilted to the open position.

The controller 25 may comprise a casing 33 in which is mounted a bellows 34 connected by a pipe 35 to the low pressure or suction line 19. The bellows 34 operates a lever 36 pivoted at 37 against the action of an adjustable tension spring 38. One end of the spring 38 is connected to the lever 36 and the other end is connected to a nut 39 screw threadedly mounted on a screw 40. By rotating the screw 40 the tension in the spring 38 may be adjusted and hence the pressure setting of the bellows 34 may be adjusted. The lever

36 operates an arm 41 guided in a guide 42 and carrying at its upper extremity a screw 43. The screw 43 is adapted to engage a lever 44 pivoted at 45 and carrying a mercury switch 46, the mercury switch 46 being biased to the open position shown by its own weight. For purposes of illustration it is assumed that when the suction pressure rises to 35 lbs. the screw 43 tilts the mercury switch to a closed position and as soon as the pressure on the low pressure side of the refrigerating apparatus decreases a relatively small amount below this 35 lbs., the screw 43 disengages the lever 44 to allow the mercury switch 46 to open if it is not latched closed at this time.

The controller 25 also includes a bellows 48 mounted in the casing 33 and connected by a pipe 49 to the high pressure line 15. The bellows 48 operates a lever 50 pivoted at 51 against the action of an adjustable tension spring 52. One end of the spring 52 is connected to the lever 50 and the other end is connected to a nut 53 screw threadedly mounted on a screw 54. By rotating the screw 54 the tension of the spring 52 is adjusted and hence the pressure setting of the bellows 48 is adjusted. Lever 50 operates an arm 55 guided in a guide 56 and carrying at its upper extremity a screw 57. The screw 57 is adapted to engage a lever 58 pivoted at 59 for closing a mercury switch 60, the mercury switch 60 being biased to the open position shown by its own weight. For purposes of illustration it is assumed that when the pressure on the high pressure side of the refrigerating apparatus decreases to 140 lbs. the screw 57 tilts the mercury switch 60 to a closed position and when the pressure rises a relatively small amount above this 140 lb. value the screw 57 disengages the lever 58 to allow the mercury switch 60 to open providing it is not latched closed at this time.

A latch means generally designated at 61 is utilized for latching the mercury switch 46 closed during operation of the compressor after the mercury switch 46 has been closed in the manner pointed out above. This latch means may comprise a bell crank lever pivoted at 63 and having arms 62 and 64. Mounted on the same pivot 63 with the bell crank lever is a latch member 65 provided with an abutment 66 for engaging the arm 62 of the bell crank lever and also provided with an arm 67. The arms 67 and 64 are provided with lugs 69 and 70 connected together by a spring 68 for holding the abutment 66 in engagement with the arm 62.

A latch means generally designated at 71 is also provided for the mercury switch 60 for holding the same closed after it has once been closed in the manner pointed out above during the operation of the compressor. This latch means 71 may comprise a bell crank lever pivoted at 73 and having arms 72 and 74. A latch member 75 is pivoted on the pivot 73 and carries an abutment 76 for engaging the arm 72. The latch member 75 also carries an arm 77, the arms 77 and 74 being provided with lugs 79 and 80, respectively, connected together by a tension spring 78 for holding the abutment 76 in engagement with the arm 72.

The latch means 61 and 71 are operated by an actuator 82 connected by a rod 83 to an armature 85, the rod 83 being guided in a guide 84. A core 86 and an operating coil 87 coact with the armature 85 to raise the armature 85 and hence the actuator 82 when the operating coil 87 is energized. Raising of the actuator 82 moves the latch means 61 and 71 outwardly to

latch the mercury switches 46 and 60 closed after they both have been closed in the manner pointed out above.

The arm 41 operated in response to changes in pressure on the low pressure side of the evaporator carries a leg 90 provided with a screw 91 for engaging the arm 67. For purposes of illustration it is assumed that when the pressure on the low pressure side of the refrigerating apparatus decreases to 10 lbs. the screw 91 will engage the arm 67 to overcome the spring 68 to release the latch member 65 from the lever 44 to allow opening of the mercury switch 46. In a similar manner the arm 55 which is operated in response to changes in pressure on the high pressure side of the refrigerating apparatus is provided with a leg 92 carrying a screw 93 for engaging the arm 77 of the latch means 71. For purposes of illustration it is assumed that when the pressure on the high pressure side of the refrigerating apparatus increases to 180 lbs. the screw 93 engages the arm 77 to move the same against the action of the spring 78 to disengage the latch member 75 from the lever 58 to allow opening movement of the mercury switch 60.

The overload cut-out mechanism generally designated at 26 may be provided with control contacts 94 and 95 carried by a spring arm 96 mounted on the bracket 97 and a pivoted lever 98, respectively. Pivoted lever 98 is provided with a cam surface 99 which coacts with a bimetallic element 100 mounted on a bracket 101. The bimetallic element 100 is heated by a heater 102 located in the energizing circuit for the compressor motor 14. Upon the occurrence of an overload condition in the compressor motor 14 the current flow through the heater element 102 becomes excessive which warps the bimetallic element 100 to the left and when the bimetallic element 100 has moved sufficiently to the left the lever 98 moves downwardly to separate the contacts 94 and 95 to interrupt the energizing circuit for the compressor motor. The bimetallic element 100 carries a contact 104 in an insulated manner which engages a contact 105 carried by an arm 106 mounted on a bracket 107 when the bimetallic element 100 flexes sufficiently far to the left to allow separation of the contacts 94 and 95. Engagement of the contacts 104 and 105 energizes an auxiliary heater 108 for flexing upwardly a bimetallic element 109 mounted on a bracket 110. Upward movement of the bimetallic element 109 engages a lug 111 on the lever 98 to reclose the contacts 94 and 95. The heater 108 is so selected that a relatively long time interval is caused to elapse before the contacts 94 and 95 are reclosed and at this time the bimetallic element 100 has cooled sufficiently to again latch the contacts 94 and 95 closed. Accordingly the overload cut-out mechanism 26 opens the energizing circuit for the compressor motor 14 upon the occurrence of an excessive current flow in the heater element 102 and automatically recloses the energizing circuit for the compressor motor after the lapse of a predetermined timed interval.

Power is supplied to the compressor motor 14 and to the control system in general by means of line wires 112 and 113 leading from some source of power (not shown).

For purposes of illustration it is assumed that the temperature of the medium within the enclosure 10 increases to 42° to close the mercury switch 31, that the pressure on the low pressure side of the refrigerating apparatus increases to

35 lbs. to close the mercury switch 46 and that the pressure on the high pressure side of the refrigerating apparatus decreases to 140 lbs. to close the mercury switch 60. This completes an energizing circuit for the compressor motor 14 which may be traced from the line wire 112 through wire 114, heater 102, wire 115, lever 98, contacts 95 and 94, arm 96, wire 116, compressor motor 14, wire 117, mercury switch 31, wire 118, mercury switch 60, wire 119, operating coil 87, wire 120, mercury switch 46, and wire 121 back to the other line wire 113. Completion of this circuit energizes the compressor motor 14 and hence places the refrigerating apparatus in operation and also energizes the operating coil 87 for raising the actuator 82 to latch the mercury switches 46 and 60 closed. The compressor motor 14 and hence the refrigerating apparatus remains in operation even though the pressure on the low pressure side of the refrigerating apparatus decreases below 35 lbs. and the pressure on the high pressure side of the refrigerating apparatus increases above 140 lbs. until such time as the temperature within the enclosure 10 decreases to 40°. When the temperature within the enclosure 10 decreases to 40° the mercury switch 31 is tilted to the off position to break the energizing circuit to the compressor motor 14 and to deenergize the operating coil 87. The latch means 61 and 71 are thereupon released and the mercury switches 46 and 60 are tilted to the off positions as shown. The refrigerating apparatus can again be placed in operation only when the pressure on the low pressure side of the refrigerating apparatus increases to 35 lbs. and the pressure on the high pressure side of the refrigerating apparatus decreases to 140 lbs.

If during the operation of the refrigerating apparatus the pressure on the low pressure side of the refrigerating apparatus decreases to 10 lbs. before the temperature in the enclosure 10 decreases to 40° the screw 91 releases the latch means 61 to allow the mercury switch 46 to open. Opening of the mercury switch 46 breaks the energizing circuit for the compressor motor 14 and deenergizes the operating coil 87 whereby both latch means 61 and 71 are returned to the positions shown in Figure 1 to open the mercury switches 46 and 60. Here again the refrigerating apparatus can again be placed in operation only when the pressure on the low pressure side of the refrigerating apparatus increases to 35 lbs. and the pressure on the high pressure side of the refrigerating apparatus decreases to 140 lbs.

If the pressure on the high pressure side of the refrigerating apparatus should increase to 180 lbs. before the temperature within the enclosure 10 decreases to 40° the screw 93 releases the latch means 71 to allow the mercury switch 60 to open. Opening of the mercury switch 60 breaks the energizing circuit for the compressor motor 14 and deenergizes the operating coil 87 to release both latch means 61 and 71 to allow opening of the mercury switches 46 and 60. After this has occurred the refrigerating apparatus may again be placed in operation only when the pressure on the low pressure side of the refrigerating apparatus increases to 35 lbs. and the pressure on the high pressure side of the refrigerating apparatus decreases to 140 lbs.

If during the operation of the refrigerating apparatus the current flow in the energizing circuit for the compressor motor 14 should become excessive the control contacts 94 and 95 of the over-

load cut-out mechanism 26 will separate to break the energizing circuit for the compressor motor 14 and deenergize the operating coil 87 to release the latch means 61 and 71 and open the mercury switches 46 and 60. Accordingly following an overload condition the refrigerating apparatus can not again be placed in operation until the pressure on the low pressure side of the refrigerating apparatus increases to 35 lbs. and the pressure on the high pressure side of the refrigerating apparatus decreases to 140 lbs. As pointed out above the overload cut-out mechanism 26 is automatically reclosed following the lapse of a predetermined timed interval so that when the overload condition no longer exists the refrigerating apparatus may be automatically restarted to maintain desired temperature conditions within the enclosure 10. Since it is impossible to start the refrigerating apparatus until the pressure on the high pressure side of the refrigerating apparatus decreases to a predetermined low value, illustratively 140 lbs., starting of the compressor against relatively high head pressures is prevented and therefore the main cause for overload conditions is eliminated in this system. Likewise the refrigerating apparatus is shut down when the pressure on the high pressure side of the refrigerating apparatus increases to a predetermined high value, say 180 lbs., or the pressure on the low pressure side of the refrigerating apparatus decreases to a low value of, say 10 lbs. Accordingly in such a system it is perfectly satisfactory to utilize an automatic resettable overload cut-out mechanism 35 since the majority of causes of overload conditions are eliminated by the control system. About the only condition which will cause the overload cut-out mechanism to trip open is a low voltage condition which is not permanent in nature or extremely detrimental to the operation of compressor motor 14. From the above it is seen that the use of an automatically resettable overload cut-out mechanism in this type of control system is extremely beneficial. Since it is impossible to start the compressor until the pressure on the low pressure side of the refrigerating apparatus increases to 35 lbs., which may be a value corresponding to the defrosting temperature of the evaporator 11, defrosting of the evaporator 11 during each cycle of operation is assured.

Other means may be utilized for causing the latch means 61 and 71 to hold the switches 46 and 60 closed during operation of the refrigerating apparatus and two of these means are shown in Figures 2 and 3.

In Figure 2 a combined ball governor and Bowden wire arrangement generally designated at 130 is utilized for this purpose. A collar 131 is 60 rigidly secured to the compressor motor shaft or compressor shaft 132 for rotation therewith. Spring straps 133 carrying weights 134 are connected to the collar 131 and to a collar 135 slidably mounted on the shaft 132. Upon rotation of the compressor motor or compressor shaft 132 the weights 134 fly outwardly to move the collar 135 towards the left. The collar 135 is provided with a groove 136 for receiving a pin 137 carried by a yoke 138. Secured to the yoke 138 is a wire 139 which in turn is attached to the actuator 82. The wire 139 is guided in a tube 140 secured at its ends by supports 141 and 142. Accordingly it is seen that when the compressor is placed in operation the actuator 82 is moved upwardly to actuate the latch means 61 and 71 to hold the mer-

cury switches 46 and 60 closed during the operation of the refrigerating apparatus. The combined ball governor and Bowden wire arrangement therefore provides exactly the same operation as the electromagnetic actuator of Figure 1 and therefore a further description is not considered necessary.

In Figure 3 the actuator 82 is operated by a fluid pump arrangement generally designated at 144. The actuator 82 is connected by a rod 145 to a diaphragm 146 which is clamped to a pressure chamber 147 by a ring 148. A fluid line 149 connects the pressure chamber under the diaphragm 146 to the discharge side of a gear pump 150 which is operated by the compressor motor shaft or the compressor shaft. Fluid is supplied to the gear pump 150 by a supply line 151 leading from a sump 142. Accordingly when the compressor is placed in operation the gear pump forces the diaphragm 146 and hence the actuator 82 upwardly to cause the latch means 61 and 71 to latch the mercury switches 46 and 60 closed during the operation of the refrigerating apparatus. When the refrigerating apparatus shuts down the fluid in the pressure chamber leaks back through the gear pump 150 to the sump 152 to allow the latch means 61 and 71 to release and cause opening of the mercury switches 46 and 60. From the above it is seen that the fluid pump arrangement 144 of Figure 3 gives substantially the same results as the electromagnetic arrangement of Figure 1 and therefore a further description is not considered necessary.

If it is not considered necessary to prevent starting of the refrigerating apparatus until the pressure on the high pressure side of the refrigerating apparatus decreases to 142 lbs. the mercury switch 60 and the latch means 71 may be omitted as is illustrated in Figure 4. In Figure 4 the bellows 48 which is operated in accordance with changes in pressure on the high pressure side of the refrigerating apparatus operates a lever 155 pivoted at 156 against the action of an adjustable tension spring 157. One end of the tension spring 157 is connected to the lever 155 and the other end is connected to a nut 158 screw threadedly mounted on a screw 159. By rotating the screw 159 the tension in the spring 157 may be adjusted and hence the pressure setting of the bellows 48 may be adjusted. Lever 155 carries a screw 160 which is adapted to engage the arm 67 of the latch means 61, for example, when the pressure on the high pressure side of the refrigerating apparatus increases to 180 lbs.

Accordingly in the construction shown in Figure 4 the mercury switch 46 is closed when the pressure on the low pressure side of the refrigerating apparatus increases to 35 lbs. and is held closed by the latch means 61 during operation of the compressor. If either the pressure on the low pressure side of the refrigerating apparatus decreases to 10 lbs. to cause the screw 91 to engage the arm 67 or the pressure on the high pressure side of the refrigerating apparatus increases to 180 lbs. to cause the screw 160 to engage the arm 67 the latch means 61 is released to allow the mercury switch 46 to open.

Power is supplied to the compressor motor 14 in Figure 4 by line wires 162 and 167 leading from some source of power (not shown). Assume now that the temperature within the enclosure increases to 42° to close the mercury switch 31 and that the pressure on the low pressure side of the refrigerating apparatus increases

to 35 lbs. a circuit is thereupon completed from the line wire 162 through control contacts 95 and 94 of the overload cut-out mechanism 26, wire 163, mercury switch 31, wire 164, mercury switch 46, wire 165, operating coil 87, wire 166, and compressor motor 14 back to the other line wire 167. Completion of this circuit causes operation of the compressor motor 14 and energization of the operating coil 87 to latch the mercury switch 46 closed. The compressor motor 14 will thereupon remain in operation until either the temperature within the enclosure should decrease to 40° or the pressure on the low pressure side of the refrigerating apparatus should decrease to 10 lbs. or the pressure on the high pressure side of the refrigerating apparatus should increase to 180 lbs. or an overload condition should occur.

The overload cut-out mechanism of this invention may also be applied to the control system shown and described in application Serial No. 101,107, filed Sept. 16, 1936, by W. R. Miller to accomplish substantially the same results as are accomplished in the control system of Figure 1. The application of the overhead cut-out mechanism 26 to the control system of the W. R. Miller application is diagrammatically illustrated in Figure 5. The compressor motor 14 is here controlled by a relay or starter generally designated at 170 and comprising an operating coil 171 for operating switch arms 172 and 173 with respect to contacts 174 and 175. When the operating coil 171 is energized the switch arms 172 and 173 are moved into engagement with their respective contacts 174 and 175 and when the operating coil 171 is deenergized the switch arms are moved out of engagement with their respective contacts by means of springs gravity or other means (not shown).

Contacts 176 and 177 are normally closed but are open when the pressure on the high pressure side of the refrigerating apparatus increases to 180 lbs. and contacts 178 and 179 are normally open but are moved to a closed position when the pressure on the high pressure side of the refrigerating apparatus decreases to 140 lbs. Contacts 180 and 181 are normally closed but are moved to an open position when the pressure on the low pressure side of the refrigerating apparatus decreases to 10 lbs. and contacts 182 and 183 are normally open but are moved to a closed position when the pressure on the low pressure side of the refrigerating apparatus increases to 35 lbs. The mercury switch 184 is operated in accordance with variations in temperature being controlled and is moved to a closed position when the temperature increases to 42° and is moved to an open position when the temperature decreases to 40°. Control contacts 94 and 95, the auxiliary contacts 104 and 105, the main heater 102 and the auxiliary heater 108 of the overload cut-out mechanism 126 are schematically shown in Figure 5. Power is supplied to the control system of Figure 5 by means of line wires 187 and 188 leading from some source of power (not shown).

Assume now that the temperature to be controlled increases to 42° to close the mercury switch 184, that the pressure on the high pressure side of the refrigerating apparatus decreases to 140 lbs. to cause contacts 178 and 179 to engage and that the pressure on the low pressure side of the refrigerating apparatus increases to 35 lbs. to cause the contacts 182 and 183 to engage. This completes a circuit from the line wire 187

through wire 189, control contacts 94 and 95 of the overload cut-out mechanism 26, wire 190, contacts 176 and 177, wire 191, mercury switch 184, wire 192, contacts 180 and 181, wires 193 and 194, contacts 183 and 182, wire 195, contacts 179 and 178, wires 196 and 197, operating coil 171, and wires 198 and 199 back to the other line wire 188. Completion of this circuit energizes the operating coil 171 to move the switch arms 172 and 173 into engagement with their respective contacts 174 and 175.

Movement of the switch arm 172 into engagement with the contact 174 completes a circuit from the line wire 172 through heater element 102, contact 174, switch arm 172, wire 200, compressor motor 14 and wires 201 and 199 back to the other line wire 188. Completion of this circuit causes operation of the compressor motor 14.

Movement of the switch arm 173 into engagement with the contact 175 completes a maintaining circuit for the operating coil 171 which is independent of the contacts 178 and 179 and the contacts 182 and 183. This circuit may be traced from the line wire 187 through wire 189, contacts 94 and 95, wire 190, contacts 176 and 177, wire 181, mercury switch 184, wire 192, contacts 180 and 181, wires 193 and 202, contact 175, switch arm 173, wires 203 and 197, operating coil 171, and wires 198 and 199 back to the other line wire 188. Completion of this circuit maintains the operating coil 171 energized and hence the refrigerating apparatus in operation until either the control contacts 94 and 95 are separated upon the occurrence of an excessive current flow through the heater 102 or the pressure on the high pressure side of the refrigerating apparatus increases to 180 lbs. or the temperature being controlled decreases to 40° or the pressure on the low pressure side of the refrigerating apparatus decreases to 10 lbs. When any of these contingencies occur the refrigerating apparatus cannot again be restarted until the mercury switch 184 is closed upon a call for cooling, the control contacts 94 and 95 of the overload cut-out mechanism 26 are reclosed, the pressure on the high pressure side of the refrigerating apparatus decreases to 148 lbs. and the pressure on the low pressure side of the refrigerating apparatus increases to 35 lbs. Accordingly the sequence of operation is substantially the same as that of the construction shown in Figure 1 although the construction of the two systems is entirely different. In Figure 5 the control contacts 94 and 95 of the overload cut-out mechanism are located in a pilot circuit while in Figure 1 they are shown to be in the energizing circuit of the compressor motor.

Although for purposes of illustration several forms of this invention have been disclosed other forms thereof may become apparent to those skilled in the art upon reference to this disclosure and therefore this invention is to be limited only by the scope of the appended claims and prior art.

I claim as my invention:

1. In a control system for a refrigerating apparatus including a compressor and evaporator means for cooling a medium, the combination of, means including switch means for controlling the operation of the compressor, means responsive to a condition which is a measure of evaporator temperature for closing the switch means when the evaporator temperature rises to a predetermined high value for operating the compressor, and latch means operated as an incident

to operation of the compressor for holding the switch means closed as long as the compressor remains in operation.

5. In a control system for a refrigerating apparatus including a compressor and evaporator means for cooling a medium, the combination of, means including switch means for controlling the operation of the compressor, means responsive to a condition which is a measure of evaporator temperature for closing the switch means when the evaporator temperature rises to a predetermined high value for operating the compressor, latch means operated as an incident to operation of the compressor for holding the switch means closed as long as the compressor remains in operation, and means operated by said condition responsive means when the evaporator temperature decreases to a predetermined low value for releasing said latch means to open said switch means and stop operation of the compressor.

3. In a control system for a refrigerating apparatus including a compressor and evaporator means for cooling a medium, the combination of, means including switch means for controlling the operation of the compressor, means responsive to the pressure on the high pressure side of the refrigerating apparatus for closing the switch means when the pressure decreases to a predetermined low value for operating the compressor, and latch means operated as an incident to operation of the compressor for holding the switch means closed as long as the compressor remains in operation.

4. In a control system for a refrigerating apparatus including a compressor and evaporator means for cooling a medium, the combination of, means including switch means for controlling the operation of the compressor, means responsive to the pressure on the high pressure side of the refrigerating apparatus for closing the switch means when the pressure decreases to a predetermined low value for operating the compressor, latch means operated as an incident to operation of the compressor for holding the switch means closed as long as the compressor remains in operation, and means operated by said pressure responsive means when the pressure increases to a predetermined high value for releasing said latch means to open said switch means and stop operation of the compressor.

5. In a control system for a refrigerating apparatus including a compressor and evaporator means for cooling a medium, the combination of, means including switch means for controlling the operation of the compressor, control means responsive to a condition which is a measure of evaporator temperature, means controlled by said control means for closing said switch means when the evaporator temperature rises to a predetermined high value for operating the compressor, latch means operated as an incident to operation of the compressor for holding the switch means closed as long as the compressor remains in operation, control means responsive to the pressure on the high pressure side of the refrigerating apparatus, and means controlled by said last mentioned control means for releasing said latch means when the pressure on the high pressure side of the refrigerating apparatus increases to a predetermined high value to open said switch means and stop operation of the compressor.

6. In a control system for a refrigerating apparatus including a compressor and evaporator means for cooling a medium, the combination of, means including switch means for controlling the

operation of the compressor, control means responsive to a condition which is a measure of evaporator temperature, means controlled by said control means for closing said switch means when the evaporator temperature rises to a predetermined high value for operating the compressor, latch means operated as an incident to operation of the compressor for holding the switch means closed as long as the compressor remains in operation, control means responsive to the pressure on the high pressure side of the refrigerating apparatus, and means controlled by both of said control means for releasing said latch means when either the evaporator temperature decreases to a predetermined low value or the pressure on the high pressure side of the refrigerating apparatus increases to a predetermined high value to open said switch means and stop operation of the compressor.

7. In a control system for a refrigerating apparatus including a compressor and evaporator means for cooling a medium, the combination of, means including switch means for controlling the operation of the compressor, control means responsive to a condition which is a measure of evaporator temperature, control means responsive to the pressure on the high pressure side of the refrigerating apparatus, means controlled by said control means for closing said switch means when both the evaporator temperature increases to a predetermined high value and the pressure on the high pressure side of the refrigerating apparatus decreases to a predetermined low value, and latch means operated as an incident to operation of the compressor for holding the switch means closed as long as the compressor remains in operation.

8. In a control system for a refrigerating apparatus including a compressor and evaporator means for cooling a medium, the combination of, means including switch means for controlling the operation of the compressor, control means responsive to a condition which is a measure of evaporator temperature, control means responsive to the pressure on the high pressure side of the refrigerating apparatus, means controlled by said control means for closing said switch means when both the evaporator temperature increases to a predetermined high value and the pressure on the high pressure side of the refrigerating apparatus decreases to a predetermined low value, latch means operated as an incident to operation of the compressor for holding the switch means closed as long as the compressor remains in operation, and means controlled by said control means for releasing said latch means when either the evaporator temperature decreases to a predetermined low value or the pressure on the high pressure side of the refrigerating apparatus increases to a predetermined high value to open said switch means and stop operation of the compressor.

9. In a control system for a refrigerating apparatus including a compressor and evaporator means for cooling a medium, the combination of, means including first and second switch means arranged in series for controlling the operation of the compressor, first control means responsive to a condition which is a measure of evaporator temperature for closing the first switch means when the evaporator temperature rises to a predetermined high value, second control means responsive to the pressure on the high pressure side of the refrigerating apparatus for closing the second switch means when the pressure decreases

to a predetermined low value, and latch means operated as an incident to operation of the compressor for holding the switch means closed as long as the compressor remains in operation.

- 5 10. In a control system for a refrigerating apparatus including a compressor and evaporator means for cooling a medium, the combination of, means including first and second switch means arranged in series for controlling the operation 10 of the compressor, first control means responsive to a condition which is a measure of evaporator temperature for closing the first switch means when the evaporator temperature rises to a predetermined high value, second control means responsive to the pressure on the high pressure 15 side of the refrigerating apparatus for closing the second switch means when the pressure decreases to a predetermined low value, latch means operated as an incident to operation of the compressor for holding the switch means closed as 20 long as the compressor remains in operation, and means operated by both of said control means for releasing said latch means when either the evaporator temperature decreases to a predetermined low value or the pressure on the high 25 pressure side of the refrigerating apparatus increases to a predetermined high value.

11. In a control system for a, refrigerating apparatus including a compressor and evaporator means for cooling a medium, the combination of, means including first and second switch means arranged in series for controlling the operation of the compressor, first control means responsive to a condition which is a measure of evaporator temperature for closing the first switch means when the evaporator temperature rises to a predetermined high value, second control means responsive to the pressure on the high pressure side of the refrigerating apparatus for closing the second switch means when the pressure decreases to a predetermined low value, and latch means for each switch means and operated as an incident to operation of the compressor for holding their respective switch means closed as long as the compressor remains in operation.

18 12. In a control system for a refrigerating apparatus including a compressor and evaporator means for cooling a medium, the combination of, means including first and second switch means 50 arranged in series for controlling the operation of the compressor, first control means responsive to a condition which is a measure of evaporator temperature for closing the first switch means when the evaporator temperature rises to a pre- 55 determined high value, second control means responsive to the pressure on the high pressure side of the refrigerating apparatus for closing the second switch means when the pressure decreases to a predetermined low value, latch means 60 for each switch means and operated as an incident to operation of the compressor for holding their respective switch means closed as long as the compressor remains in operation, means operated by the first control means for releasing the 65 latch means of the first switch means when the evaporator temperature decreases to a predetermined low value to open the first switch means, and means operated by the second control means for releasing the latch means of the second 70 switch means when the pressure on the high pressure side of the refrigerating apparatus increases to a predetermined high value to open the second switch means.

13. In a control system for a refrigerating apparatus including a compressor and evaporator

evaporator temperature decreases to a predetermined low value or the pressure on the high pressure side of the refrigerating apparatus increases to a predetermined high value to open the second switch means.

19. In a control system for a refrigerating apparatus having an electrically operated compressor and evaporator means for cooling a medium, the combination of, an energizing circuit for the electrically operated compressor, means including control means responsive to the pressure on the high pressure side of the refrigerating apparatus for closing the energizing circuit and operating the compressor only when the pressure on the high pressure side of the refrigerating apparatus decreases to a predetermined low value whereby starting of the compressor against high head pressures is prevented, switch means for controlling the energizing circuit, means responsive to the current flow through the energizing circuit for tripping open the switch means for opening the energizing circuit in response to an excessive current flow, and means operative upon opening of the switch means for automatically reclosing the switch means after a time interval has elapsed.

20. In a control system for a refrigerating apparatus having an electrically operated compressor and evaporator means for cooling a medium, the combination of, an energizing circuit for the electrically operated compressor, control means responsive to the pressure on the low pressure side of the refrigerating apparatus, control means responsive to the pressure on the high pressure side of the refrigerating apparatus, means controlled by said control means to close the energizing circuit and operate the compressor only when the pressure on the low pressure side of the refrigerating apparatus increases to a predetermined high value and the pressure on the high pressure side of the refrigerating apparatus decreases to a predetermined low value and for maintaining the energizing circuit closed and the compressor in operation until either the pressure on the low pressure side of the refrigerating apparatus decreases to a predetermined low value or the pressure on the high pressure side of the refrigerating apparatus increases to a predetermined high value, overload cut-out means for controlling the energizing circuit including control means tripped open upon the occurrence of an excessive current flow through the energizing circuit for opening the energizing circuit, and means operative upon opening of the control means for automatically reclosing the control means following the lapse of a predetermined time interval.

21. In a control system for a refrigerating apparatus including a compressor and evaporator means for cooling a medium, the combination of, first switch means, first control means responsive to the condition of the medium being cooled for closing the first switch means upon a demand for cooling and for opening the first switch means when the cooling demand is satisfied, second switch means, second control means responsive to a condition which is a measure of evaporator temperature, third control means responsive to the pressure on the high pressure side of the refrigerating apparatus, means controlled by the second and third control means to close the second switch means when both the evaporator temperature increases to a predetermined high value and the pressure on the high pres- 75

sure side of the refrigerating apparatus decreases to a predetermined low value, means controlled by the first and second switch means for operating the compressor when both switch means are closed, latch means operated as an incident to operation of the compressor for holding the second switch means closed as long as the compressor remains in operation, means controlled by the second and third control means for releasing the latch means when either the evaporator temperature decreases to a predetermined low value or the pressure on the high pressure side increases to a predetermined high value to open the second switch means, overload cut-out means for the compressor including switch means for additionally controlling the operation of the compressor, means for latching the switch means closed, means responsive to a compressor overload condition for releasing the last mentioned latch means to cause the last mentioned switch means to open for stopping operation of the compressor, and means operative upon opening of the last mentioned switch means for automatically reclosing the switch means and latching the same closed following the lapse of a predetermined time interval.

22. In a control system for a refrigerating apparatus including a compressor and evaporator means for cooling a medium, the combination of, 30 means including control means responsive to a condition which is a measure of evaporator temperature for starting operation of the compressor only when the evaporator temperature rises to a predetermined high value and means operated directly and mechanically by the compressor for maintaining the compressor in operation.

23. In a control system for a refrigerating apparatus including a compressor and evaporator means for cooling a medium, the combination of, 40 first control means responsive to a condition of the medium being cooled which is a measure of the cooling requirements of the medium, second control means responsive to a condition which is a measure of evaporator temperature, means controlled by both control means for starting operation of the compressor only when the first control means demands cooling and the evaporator temperature increases to a predetermined high value, and means operated directly and mechanically by the compressor for maintaining the compressor in operation until the first control means becomes satisfied.

24. In a control system for a refrigerating apparatus including a compressor and evaporator means for cooling a medium, the combination of, 55 first switch means, first control means responsive to a condition of the medium being cooled which is a measure of the cooling requirements of the medium for closing the first switch means upon a demand for cooling and for opening the first switch means when the cooling demand is satisfied, second switch means, second control means responsive to a condition which is a measure of evaporator temperature for closing the second switch means when the evaporator temperature rises to a predetermined high value, means controlled by the first and second switch means for operating the compressor when both switch means are closed, latch means for holding the second switch means closed, and an electromagnet energized as an incident to operation of the compressor for operating the latch means to hold the second switch means closed as long as the compressor remains in operation.

25. In a control system for a refrigerating ap-

paratus including a compressor and evaporator means for cooling a medium, the combination of, first control means responsive to a condition of the medium being cooled which is a measure of the cooling requirements of the medium, second control means responsive to a condition which is a measure of evaporator temperature, means controlled by both control means for starting operation of the compressor only when the first control means demands cooling and the evaporator temperature increases to a predetermined high value and means actuated by operation of the compressor for maintaining the compressor in operation until the first control means becomes satisfied.

26. In a control system for a refrigerating ap-

paratus including a compressor and evaporator means for cooling a medium, the combination of, first control means responsive to a condition of the medium being cooled which is a measure of the cooling requirements of the medium, second control means responsive to a condition which is a measure of evaporator temperature, means controlled by both control means for starting operation of the compressor only when the first control means demands cooling and the evaporator temperature increases to a predetermined high value and means actuated by operation of the compressor for maintaining said second control means in compressor operating position until the first control means becomes satisfied.

CHARLES B. SPANGENBERG.
